UNITED STATES PATENT OFFICE.

JAMES WILSON FOUST, OF ROCK FALLS, ASSIGNOR TO THOMAS A. GALT
AND GEORGE S. TRACY, OF STERLING, ILLINOIS.

HAY-LOADER.

SPECIFICATION forming part of Letters Patent No. 329,383, dated October 27, 1885.

Application filed September 10, 1884. Serial No. 142,633. (No model.)

To all whom it may concern:

Be it known that I, JAMES WILSON FOUST, a citizen of the United States, residing at Rock Falls, in the county of Whiteside and State of Illinois, have invented certain new and useful Improvements in Hay-Loaders; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention has reference to improvements in that class of hay-loaders in which a revolving rake casts the hay upon an elevator, and pertains more especially to certain novel mechanism in the following particulars: First, 20 in providing an adjustable bed for the bars which carry the rake-teeth, whereby such bars may yield toward the center of the revolving rake and prevent breakage of the parts when passing over obstructions or inequalities in the 25 surface of the ground; second, in pivoting the rake-bars eccentrically, so that the gravity of such bars will turn the teeth to and hold them in a vertical position when not otherwise positively affected, as hereinafter described; third, 30 a trip-lever pivotally seated on the rake journal-box, to guide the rake-teeth between the slats of the elevator in backing or turning the rake; fourth, the provision of a forked shoe to bestride the rear of the rake-head and prevent 35 the hay from wedging between such wheel and the frame of the machine; fifth, the interposition of a carrying-spur to sustain the elevator-chain clear of the rake-bars.

As my present invention consists of certain 40 improvements on the hay-loader for which Letters Patent of the United States were granted me November 18, 1862, No. 36,947, and also October 16, 1866, No. 58,804, I do not deem it necessary to show or describe anything further than the parts containing my 45 present invention and their mode of attachment to the machine.

In the drawings, Figure 1 is a view in perspective of part of a machine embodying my 50 invention. Fig. 2 is an end view of one of the

rake-bars, showing the mode of pivoting such bar in the spoke of the rake-head. Fig. 3 is a detached view of the shoe for keeping the rake-head clear of hay. Fig. 4 is an end view of the axle, showing the trip-lever.

55

A is the frame of the machine.

B B are the carrying-wheels and also the heads of the rake, and are rigidly attached to the axle C, the latter being suitably journaled at points outside of such wheels to the frame A.

60

D D are the oscillating bars which carry the teeth D'.

E E are arms, bent at right angles, used for pivotally hanging the bars D in the spokes F of the rake-heads B. The inner ends of the 65 arms E consist of a collar, a, which is rigidly fastened around the end of the bar D, with the horizontal portion of the arm E on the same side of the center of such bar from which the teeth D' project, so that when such bar is hanging loosely in the spokes F, supported by the horizontal part of the arm E, the rake-teeth will point upward in nearly or quite a vertical position, by reason of the center of gravity of the rake-bar being below its points of support.

70

The teeth D' are placed in any suitable mode upon the rake-bar D so as to project in a line from one side of the latter. In each spoke F, and lengthwise thereof, is formed an elongated slot, b, and also a socket, c, extending from the 80 inner end of such slot a short distance toward the center of the wheel B. In the socket c is placed a coiled spring, d, which extends nearly to the outer end of the slot b. A short pin, e, having a concave head, is placed on the under side of 85 the horizontal portion of the arm E, and projected into the spring d where the arm E is placed in the slot b, the horizontal part of the arm E resting and oscillating in the concavity of the head of the pin e. The pin e serves to 90 hold the outer end of the spring d in place, while the inner end of such spring is contained in the socket c. By this construction the horizontal part of the arm E, which forms the pivotal bearing of the bar D, is adjustably 95 held by the spring d against the outer end of the slot b, and as the outer end of such slot is downward when its rake-bar is next the ground, the pressure of any obstacle or unevenness of the surface of the ground will be 100

provided for by the bar D yielding inward or toward the center of the rake, thereby avoiding undue strain upon or breakage of the parts. The portion of the arm E which supports the bar D being outside of the line of the latter, it is obvious that the bar D will of its own gravity swing under the line of such support and turn the teeth upward when free so to do. On one end of each rake-bar D the outer end of the arm E is formed into a guide-arm, G, and for convenience such arm is placed alternately at different ends of the succeeding rake-bars D. On the outside of the wheel B, and extending inwardly from its rim, are formed the flanges H, and attached to the frame A is a segment, I. The arm G is of such conformation, and the flanges H and segment I in such relation, that in the rotation of the rake the outside of such arm G, after the bar D has started on its downward movement, rests upon the flange H, and the lower side of the outer or free end of such arm G engages the lower end of the cam or segment I, and is forced upward past the lower end of such cam by the orbital movement of the rake-bar until such rake-bar has made a half-axial revolution, when the arm G is dragged under the cam, with its convex side upward, by the onward movement of the rake-bar, and is guided by such cam until the rake-bar D has completed sufficient of its upward movement to cast the hay upon the elevator K. This guiding of the arm G between the flanges H and segment I has the effect of bringing the rake-teeth downward in a position to rake the hay from the ground and to turn such teeth in a position to throw the hay upward and forward upon the elevator K, and when this is accomplished, and the arm G passed beyond the upper end of the segment I, the bar D being released automatically swings into a position with the teeth D' upward, and in that position passes downward from between the slats of the elevator K, leaving the hay upon the latter. It is sometimes necessary to move the machine backward, and in such event the rake-teeth are apt to come in contact with the slats of the elevator. In order to prevent this, I place a trip-lever, L, inside of the frame A, on the iron box in which the axle C is journaled. The lever L is pivoted near its front end so that its rear end rests upon the said box, while its front end is somewhat elevated. In the forward movement of the rake the le-

ver L has no operation, but in the backward movement of the rake the free end of the lever L engages the lower end of the arm G, and guides the teeth D' between the slats of the elevator.

M is a forked shoe, suitably attached to the frame A in such a position as to loosely encircle the rim of the wheel B at the rear of the latter slightly below its center, leaving at the front end of such shoe an open interval sufficient only for the passage of the spokes F and flanges H. The purpose and function of the shoe M is to prevent the loose hay from wedging between the wheel and the frame.

N N are horizontal spurs formed on the inside of the spokes F outside of the slots b. On these spurs are sustained and carried the elevator-chains O, and the latter are thereby prevented from resting on the roller-bars D, or interfering with the flexibility or operation of the latter.

In former constructions, where the rake-bars D had no movement to or from the center of the rake, the elevator-chains could be carried on such rake-bars, but in my invention to permit the elevator-chains to rest upon the rake-bars would force the latter too much toward the center of the rake, and would otherwise impede their operation.

What I claim as my invention, and desire to secure by Letters Patent of the United States, is—

1. The combination of the rake-head B, provided with radial slots b, the rake-bar D, seated in such slot, and the spring d, whereby such rake-bar is rendered flexible in the line of such slot, substantially as shown, and for the purpose described.

2. The combination of the wheel B, provided with radial slots b, the rake-bar D, seated in such slots, the arm E, the arm G, spring d, and cam I, substantially as shown, and for the purpose described.

3. The combination of the trip-lever L, spokes F, and bars D, provided with the arms G, substantially as shown, and for the purpose specified.

In testimony whereof I affix my signature in presence of two witnesses.

JAMES WILSON FOUST.
